CLAIM

The ornamental design for a keyboard for tablet computer, as shown and described.

DESCRIPTION

1. Keyboard for tablet computer

1.1 : Perspective

1.2 : Rear perspective view

1.3 : Top

1.4 : Bottom

1.5 : Right

1.6 : Left

1.7 : Back

1.8 : Front

1.9 : Referential rear perspective view

The feature of the claimed design resides in the shape and configuration of the rear part of the keyboard, being equipped with a pen holder; the pen holder can house a pen in either of a rightward or leftward direction; the broken lines shown in the drawings illustrate portions of the keyboard that form no part of the claimed design.
